[57] CLAIM

The ornamental design for an extrusion for a frame, as shown and described.

DESCRIPTION

FIG. 1 is a top view of an extrusion for a frame, showing the new design;

FIG. 2 is an inner side view of an extrusion for a frame, thereof;

FIG. 3 is a cross-section view of an extrusion for a frame, thereof;

FIG. 4 is an outer side view of an extrusion for a frame, thereof; and,

FIG. 5 is a bottom view of an extrusion for a frame, thereof. The extrusion for a frame is broken in the center to indicate indeterminate length.
